INDEX AND SIGNAL ARRANGEMENT

Raymond C. Finch, Jamestown, N. Y., assignor
to Art Metal Construction Company, Jamestown, N. Y., a corporation of Massachusetts

Application March 15, 1939, Serial No. 262,013

2 Claims. (Cl. 129—16.7)

This invention relates to an index and signal arrangement for paper files of the self-indexing type in which either the record-bearing elements themselves or the supports therefor are arranged with identification-receiving margins in overlapping relationship. In one case, a sheath is attached to the record-bearing element itself, and in the other case is attached directly to the support. In either case, the signal device is a folded structure which embraces and rides upon the upper edge of the front wall of the sheath and cooperates with indicia disposed on the front face of the record-bearing member and appearing through the front wall of the sheath.

The invention will be best understood by reference to the following description when taken in connection with the accompanying drawing of one specific embodiment thereof while its scope will be pointed out more particularly in the appended claims.

In the drawing:

Fig. 1 is a front elevation of an index and signal arrangement embodying the invention;

Fig. 2 is a portion of Fig. 1 on a greatly enlarged scale; and

Fig. 3 is a sectional view on line 3—3 of Fig. 2.

Referring to the drawing and to the embodiment of the invention illustrated therein by way of example, there is shown an index and signal arrangement comprising a signal member 6 folded upon itself and having two downwardly-directed walls 8 and 10, a transparent sheath member 12 having two upwardly-directed walls 14 and 16, one of which, herein the wall 14, is received between said downwardly-directed walls, and a third member 18 having a portion received between one of said downwardly-directed walls and one of said upwardly-directed walls.

In the example shown, the member 18 is attached to the remaining upwardly-directed wall 16 as by providing the latter with a downwardly-directed lip 20, and by providing the member 18 with an upwardly-directed wall 22 received between the wall 16 and the lip 20. In this example, the member 18 is the rear fold of a record element 24 having a front fold 26. Where, as in the present embodiment, the front and rear folds are intended to receive records, the front fold extends downwardly fairly close to the sheath, but where, as already intimated, the folded sheet is to be merely a support for a record-bearing element, the front fold will be made relatively narrow, the record-bearing element will have its lower margin inserted in the sheath, and the upper margin of the record-bearing element will

either be tucked beneath the front fold or will be secured to it. In either case, suitable means such as a supporting wire 28 will be provided to support the filing element on an appropriate panel, and where the latter, as is commonly the case, is provided with channels to receive the ends of the wires, the latter will be provided with spacers 30 to space the wires and to maintain the desired exposure or overlap of the lower margins of the filing elements. As herein shown, the wire 28 has its greater portion received within the fold of the element 24 and the latter is provided with perforations 32 through which the terminal portions of the wire emerge from the fold.

Returning now to the signal member 6, it will be observed that the fold of the latter is arranged to rest upon and to be supported by the upper edge of the upwardly directed wall 14, along which it can slide to cooperate with appropriate indicia on that portion of the member 18 which is exposed to view through the upwardly directed wall 14 of the sheath 12. As shown, the lower margin of the member 18 is provided with a series of vertical lines 34 separated by spaces 36 on which appropriate characters or symbols such as the numerals 1 to 12, inclusive, representing months, are displayed.

Reverting once more to the signal member 6, to prevent accidental movement of the latter on the upstanding wall 14, the signal member is suitably constructed to grip the interposed wall firmly along front and rear faces over a considerable area of each and to press flatwise with spring tension against each face, to the end that it will require an intentional effort to move the signal, thus preventing error in relation to the indication which it is intended to afford. However, it is preferred to make the signal member of suitably colored Celluloid because this affords the desired characteristics of a signal, and as Celluloid used alone in this situation would not be apt to provide a sufficiently firm grip, it is preferred to reinforce the Celluloid as by providing a folded, metallic lining and reinforcing member 38 within the signal member 6 and provided with downwardly-directed walls 40 and 42 which contact the front and rear faces of the upstanding wall 14. The metal chosen for this purpose resists permanent distortion to a considerable degree and is shaped so that its walls must be sprung apart to receive the interposed wall 14. To attach the reinforcement to the signal, the reinforcement is provided with prongs

44 and 46 passed through the walls 8 and 10, respectively, and clinched.

While the use of a reinforcement such as described is preferred, it is possible that by appropriate selection of material and form of the signal member itself, the reinforcement might be eliminated. In any case, however, the folded, inverted, U shape of the signal member is a valuable and useful characteristic wholly apart from the separate reinforcing member herein described, and the signal member itself may be made of metal of the aforesaid characteristics and covered, if desired, with a colored substance.

Although the force required to move the signal is desirably great, thereby preventing accidental movement of the signal, nevertheless, inasmuch as the sheath is interlocked with the supporting member 18, displacement of the sheath on the latter is unlikely.

Having thus described one embodiment of the invention, what I claim, and desire by Letters Patent to secure is:

1. In a paper file, the combination of a signal member having two downwardly-directed, parallel walls, a folded, metallic lining and reinforcing member within said signal member, a transparent, sheath member folded upon itself and having two upwardly-directed walls, one of which has a single thickness only gripped flatwise by and between said downwardly-directed walls and by said reinforcing member, and a record member interlocked with the remaining upwardly directed wall. 5

2. In a paper file, the combination of a supporting member, a sheath member having upwardly-directed walls which embrace said supporting member, a signal member having downwardly-directed walls which embrace one of said upwardly-directed walls, and a reinforcing member which furnishes a spring tension tending to press said downwardly-directed walls toward adjacent faces, respectively, of the upwardly-directed wall which they embrace. 10 15 20
